UNITED STATES PATENT OFFICE.

CHARLES RUSSELL LANG, OF CATHCART, GLASGOW, SCOTLAND.

CONTROL OF STEAM-TURBINE-DRIVEN BOILER-FEED PUMPS

1,041,492.

Specification of Letters Patent. Patented Oct. 15, 1912.

Application filed June 3, 1912. Serial No. 701,292.

To all whom it may concern:

Be it known that I, CHARLES RUSSELL LANG, a subject of the King of Great Britain and Ireland residing at Cathcart, Glasgow, Scotland, have invented certain new and useful Improvements in the Control of Steam-Turbine-Driven Boiler-Feed Pumps, of which the following is a specification:

10 The present invention relates to the control of rotary boiler-feed pumps driven by steam turbines and is particularly applicable to marine installations.

15 The invention consists in a novel feed pump control which will be described in the following specification and more particularly set forth in the annexed claims.

On board ship the water of condensation from the main condensers is commonly discharged by the air pump into a reservoir or feed tank from which it is drawn by the feed pump for discharge into the boiler. A circuit is thus established from the feed pump to the boiler, through the steam pipe 20 to the main engine, from the engine to the condenser, from the condenser to the air pump, air pump to feed tank, and feed tank back to feed pump. The total amount of water in this circuit is approximately constant—any small wastage being made up by auxiliary feed—and in large installations the capacity of the feed tank bears a very small proportion to the quantity of water in circulation, so that a variation in the water 25 level of the boilers, without extra water being put into the system, might easily empty the feed tank. Further, it is characteristic of turbine driven feed pumps that, should the feed tank become empty and the pump 30 in consequence draw air, the load on the turbine driving the pump becomes very small and its speed of rotation rapidly accelerates. Such turbine-driven pumps are generally fitted with a safety governor, which, under 35 the above conditions, completely cuts off steam to the turbine and stops the pump. Before the pump can be started, the governor must be reset. This is an operation requiring a certain amount of time and, with 40 water-tube boilers with a comparatively small quantity of contained water, involves a dangerous delay.

The object of my present invention is to obviate this delay.

45 Referring to the accompanying drawings:—Figure 1 is an elevation, partly in

section, of a device according to my invention, the float being located in a vessel connected with the feed tank. Fig. 2 shows a similar device but with the float located in a direct-contact feed heater which is on the suction side of the pump and the discharge side of the feed tank or hot well.

In both figures *a* is the boiler feed pump and *b* is the steam turbine which drives it. *c* is the suction to the pump and *d* the discharge.

e is the steam pipe by which the turbine is fed with steam and *f* is a stop valve on this pipe. This throttle valve *g* is also provided on this steam pipe and is actuated by the lever *h* which is connected by the link *k* to the lever *m*. This lever *m* is arranged to support the float.

My invention is not confined to any particular mechanism for supporting the float, but a convenient mechanism is shown in Figs. 1 and 2. The mechanism is identical in these two figures but the float is shown only in Fig. 1.

The float *o* is suspended at the bottom of the link *p* which is pivoted to the levers *q* and *r* which are keyed respectively on the spindles *s* and *t*. The spindle *t* passes through the side of the vessel containing the float; and outside the vessel the lever *m* is keyed on this spindle. A weight *u* may, if desired, be provided on the free end of the lever *m* to balance the weight of the float and its supporting mechanism.

When the float is in its upper position, the throttle valve *g* is full open and, when the float is in its lower position, the throttle valve is sufficiently closed to reduce the speed of rotation of the pump to an extent just sufficient to prevent its pumping water into the boilers.

In Fig. 1 the float is inclosed in the vessel *v* into which the feed water can flow by way of the pipe *w* from the feed tank *x*. *y* is an equilibrium pipe connecting the top of the vessel *v* with the top of the feed tank. The feed pump suction pipe *c* draws from the bottom of the vessel *v*.

In Fig. 2 the float is located in the lower end of the direct-contact feed heater 2. The feed pump suction pipe *c* draws from the bottom of this heater while the feed from the hot well is admitted to the heater by the pipe 3. 4 is a steam connection whereby exhaust steam is admitted to the heater for heating purposes.

If the normal speed of rotation of the turbine-pump shaft is above its critical velocity, that is the angular velocity at which excessive vibration occurs, the speed is reduced by the float mechanism to an extent which still keeps it above the critical velocity while preventing the generation of water pressure sufficient to deliver water into the boiler against the pressure therein.

10 Vibration and risk of injury through the shaft rotating at its critical velocity are thus obviated.

My invention is not limited in its application to pumps driven direct by steam turbines but applies also in cases where the turbine drives the pump through speed-reducing gearing, and in such cases the critical velocity to be considered is that of the higher-velocity shaft, that is, the turbine

20 shaft.

Having now particularly described my invention, what I claim as new and desire to secure by Letters Patent is:—

1. In combination, a boiler, a rotary pump adapted to supply water to said boiler, a steam turbine adapted to drive the said pump, a steam pipe adapted to convey steam to the said turbine for the purpose of driving it, a throttle valve on said steam pipe, a float 25 located in a vessel from which the said pump draws its water, and means whereby said float can reduce the speed of rotation of said turbine to a velocity below that necessary to deliver water into said boiler against the 30 pressure therein.

2. In combination, a boiler, a rotary pump adapted to supply water to said boiler, a steam turbine adapted to drive the said pump, a steam pipe adapted to convey steam 35 to the said turbine for the purpose of driving it, a throttle valve on said steam pipe, a float located in a vessel from which the said pump draws its water, and means whereby said float can operate said throttle valve to

reduce the speed of rotation of said turbine 4 to a velocity below that necessary to deliver water into said boiler against the pressure therein, and above the critical velocity of the said turbine.

3. In combination, a boiler, a feed tank 5 adapted to contain feed water for said boiler, a rotary pump adapted to supply water to said boiler, a steam turbine adapted to drive said pump, a steam pipe adapted to convey steam to said turbine for the purpose of 55 driving it, a throttle valve on said steam pipe, a float located in a vessel from which the said pump draws its water and which is connected to and supplied with water from the said feed tank, and means whereby 60 said float can operate said throttle valve to reduce the speed of rotation of said turbine to a velocity below that necessary to deliver water into said boiler against the pressure 65 therein.

4. In combination, a boiler, a feed tank adapted to contain feed water for said boiler, a rotary pump adapted to supply water to said boiler, a steam turbine adapted to drive said pump, a steam pipe adapted to 70 convey steam to said turbine for the purpose of driving it, a throttle valve on said steam pipe, a float located in a vessel from which the said pump draws its water and which is connected to and supplied with 75 water from the said feed tank, and means whereby said float can operate said throttle valve to reduce the speed of rotation of said turbine to a velocity below that necessary to deliver water into said boiler against the 80 pressure therein, and above the critical velocity of the said turbine.

In testimony whereof, I affix my signature in presence of two witnesses.

CHARLES RUSSELL LANG.
